UNITED STATES PATENT OFFICE.

LOUIS STOCKSTROM, OF ST. LOUIS, MISSOURI, ASSIGNOR OF ONE-HALF TO
CHARLES A. STOCKSTROM, OF SAME PLACE.

DESIGN FOR A VAPOR-STOVE.

SPECIFICATION forming part of Design No. 21,653, dated June 21, 1892.

Application filed May 17, 1892. Serial No. 433,370. Term of patent 7 years.

To all whom it may concern:

Be it known that I, LOUIS STOCKSTROM, of the city of St. Louis, in the State of Missouri, have invented and produced a new and original Design for Vapor-Stoves, of which the following is a specification, reference being had to the accompanying drawing, forming part thereof.

The drawing is a perspective view of the stove, showing the novel features of the design.

The leading features of my design consist of a closed body of a parallelopipedon shape, a top plate projecting over the body, a back plate above the top plate, and panels in the front of the body.

1 represents an inclosed body having a base 2.

3 are the side walls of the stove.
4 is a lower panel in the front of the body, 20
5 a middle panel, and 6 an upper panel.

7 is a top plate projecting over the body.
8 are spider-frames located in the top-plate openings.

9 is a back plate.
10 is a cylindrical body forming a top ornament. 25

I claim as my invention—
The design for a vapor-stove, substantially as shown and described.

LOUIS STOCKSTROM.

In presence of—

ALBERT M. EBERSOLE,
E. S. KNIGHT.
